UNITED STATES PATENT OFFICE

145,275

DESIGN FOR A BOTTLE

Myron E. Scott, Dayton, Ohio

Application September 30, 1944, Serial No. 115,533

Term of patent 3½ years

(Cl. D58—6)

To all whom it may concern:

Be it known that I, Myron E. Scott, a citizen of the United States, residing at Dayton, in the county of Montgomery and State of Ohio, have invented a new, original, and ornamental Design for a Bottle, of which the following is a specification, reference being had to the accompanying drawing, forming a part thereto.

I claim:

The ornamental design for a bottle, as shown.

MYRON E. SCOTT.
